CLAIM

The ornamental design for a suction cup, as shown and described.

DESCRIPTION

FIG. 1 is a perspective view of a suction cup, viewed from front, top, and right direction, showing my new design; FIG. 2 is another perspective view thereof, viewed from rear, bottom, and left direction;

FIG. 3 is a front elevation view thereof; the rear elevation view being the same;

FIG. 4 is a left side elevation view thereof; the right side elevation view being the same;

FIG. 5 is a top plan view thereof;

FIG. 6 is a bottom plan view thereof; and,

FIG. 7 is a cross-sectional right side elevation view thereof, taken along the line of 7-7, of FIG. 3.

The broken lines in the figures are for the purpose of illustrating portions of the suction cup that form no part of the claimed design.
